UNITED STATES PATENT OFFICE

98,680

DESIGN FOR A TRANSIT PLATE

Adolph Langsner, Chicago, Ill., assignor to Eugene Dietzgen Company, Chicago, Ill., a corporation of Delaware

Application August 25, 1934, Serial No. 53,058

Term of patent 14 years

To all whom it may concern:

Be it known that I, Adolph Langsner, a citizen of the United States, residing at Chicago, Cook County, Illinois, have invented a new, original, and ornamental Design for a Transit Plate, of which the following is a specification, reference being had to the accompanying drawing, forming part thereof.

Figure 1 is a top plan view of a transit plate showing my new design; and

Figures 2 and 3 are side views of the same taken at right angles to each other.

The dominant features of applicant's design

reside in forming the adjusting nut with spheroidal surfaces and in merging the surfaces of the nut mounting with the surfaces of the plate so that the whole has an integrated unitary appearance. Further features reside in rounding the edges of the plate as well as the end of the nut mounting in order to impart a streamline appearance in the plate.

I claim:

The ornamental design for a transit plate as shown and described.

ADOLPH LANGSNER.
